UNITED STATES PATENT OFFICE.

HAROLD A. McCLELLAN, OF GROTON, CONNECTICUT.

FASTENING MEANS FOR DEMOUNTABLE RIMS.

Application filed April 17, 1922. Serial No. 553,380.

This invention relates to fastening means for rims for pneumatic tires, and it has for its object to provide a novel and simple device for holding and locking the demountable rim in tire-engaging position so that the rim may be quickly and easily assembled and disassembled therefrom.

A further object of this invention resides in providing an improved threaded connection between the parts of the felly band for locking the demountable rim quickly and easily in position; which parts, by reason of their construction, avoid the difficulties arising by the sticking together of such sections, due to rusting.

These and other objects will be apparent from a perusal of the following specification when taken in connection with the accompanying drawing, in which—

20 Figure 1 is a view partly in section of my assembled device;

Fig. 2 is an enlarged sectional view thereof, and

25 Fig. 3 is a sectional view partly in perspective of the two-part rim, clearly showing the screw thread by means of which they are connected together.

Referring specifically to the drawing, the felly 1 is provided with a felly band including the rim 2 having a laterally extending retaining flange 3 and a screw thread 4 which preferably is arranged as a quadruple radius thread, rolled, cut or cast in the felly rim in any desired manner.

30 This screw thread 4 threadedly receives a retaining ring 5 likewise similarly threaded so that the retaining ring can make threaded locking connection with the felly rim 2. This retaining ring 5 is provided with an offset lug 6 having a bore in its outer end to receive a headed bolt 7 which threads through a nut 8 secured to the felly 1 of the wheel. The construction is such that bolt 7 may rotate relatively to lug 6, but is not

45 capable of moving endwise therethrough. This retaining ring 5 is provided on its outer face with an outwardly projecting flange 9 corresponding with the flange 3 on the felly rim 2.

50 These two flanges 3 and 9 are adapted to clinch between them two detachable sections of the demountable rim proper. These sections comprise a rim 10 including a substantially flat horizontal portion 11 and an outwardly projecting flange 12. The flat portion 11 is provided on its inner face with a

preferably quadruple radius thread 13 likewise rolled, cut or cast, which thread engages in a corresponding thread 14 formed in the outer surface of the other section of 60 the demountable rim, represented as a detachable flange 15. The flange 12 of the rim and the detachable flange 15 are adapted to clinch between them the shoe of the tire as clearly illustrated in Fig. 1. In order 65 to positively lock the detachable flange 15 and rim 11 in position after they are threaded together, there is provided a spring clip 16 which is fast to the inner surface of the rim section 10 and is provided with a lug 70 17 which snaps into a hole 18 in the adjacent face of the detachable flange 15.

Particular attention is drawn to the specific arrangement of the threads which are peculiarly adapted as a means for providing the effective and sure detachability of the sections 2 and 5. The particular effectiveness of the construction is due in a great measure to the cross sectional contour of the threads which are specifically known as radius threads. By means of the special construction of these threads, the more extended peripheral bearing surface is taken advantage of to provide a more effective fastening. So also, the rounded surface of the periphery of the threads tends to eliminate the sticking which is so prevalent with the V-type of thread, and which is due in a great measure to the points and sharp angles of the V or similar type threads. So also, the 80 effective locking of the threads is secured, due to the fact that the opposite inner portions of the tire spread outwardly against the inner faces of the flanges 15 and 12 and these in turn press outwardly against the flanges 3 and 5 which in turn transmit the pressure to the inner surface of the round periphery of the thread 4, thereby securely locking the sections from longitudinal movement.

100 It is obvious from the above drawing and description that when it is desired to mount the tire on the wheel, the shoe of the tire is clinched between the flanges 12 and 15 by threading the detachable flange to the rim 105 and snapping the clip 16 into retaining position. The two sections of the demountable rim are then placed in position on the felly band between the flange 3 and the flange 5 of the retaining ring, which is then given a peripheral movement thereby threading the retaining ring into position to clinch the two 110

sectioned rim to the felly. The bolt 7 is then threaded to nut 8 thereby to draw together and lock the parts in assembled position. It is to be noted that the bolt 7 is inclined toward the felly. It is highly desirable to have this line of inclination substantially parallel to the line of inclination of the thread, so that the drawing together of the threaded sections is easier.

10 The invention as thus described constitutes a very simple, cheap and convenient means for firmly and effectively mounting a tire on a wheel.

15 It is obvious that minor changes in the details of construction and the arrangement of the parts may be made without departing from the spirit of the invention as set forth in the appended claims.

20 Having thus described the invention, what I claim as new and desire to secure by Letters Patent, is—

25 1. In a device of the class described, the combination of a tire engaging rim, a felly rim having an upstanding flange along one side engaging one of the sides of said tire engaging rim and provided adjacent its opposite side with a thread, a retaining ring having a flat portion disposed between said tire engaging rim and felly rim and threaded on its inner side to engage the thread on said felly rim, said retaining ring having a lateral upstanding flange adapted to engage the opposite side of said tire engaging rim, and means to lock said felly rim and retaining ring in threaded engagement, said means serving to tighten said ring into and hold the same in threaded engagement with said felly rim.

30 2. In a device of the class described, the combination of a tire engaging rim, a felly

rim having a flat portion formed on its outer face substantially adjacent one edge, with rolled threads of radius type, and provided at its other edge with an upstanding flange adapted to contact with one side of the tire 45 rim, a retaining ring provided with a flat portion formed with counterpart threads on its inner side engaging the threads of said felly rim and formed with an upstanding flange contacting with the opposite side of 50 said tire rim, and means for locking said threaded parts in engagement, said means serving to tighten said ring into and hold the same in threaded engagement with said felly rim.

55 3. In a device of the class described, the combination of a tire engaging rim, a felly rim comprising detachable sections adapted to engage opposite sides of the tire engaging rim, said sections having inter-engaging, quadruple, rolled-threads of the radius type, and means for holding said threaded sections in locked engaging position, said means serving to tighten said ring into and hold the same in threaded engagement with 60 said felly rim.

65 4. In a device of the class described, the combination of a tire engaging rim, a felly, a nut carried thereby, a felly rim adapted to form a clamping member for one side of said tire engaging rim, a retaining ring adapted to form a clamping member for the other side of said rim, said felly rim and retaining ring having similarly formed inter-engaging radius threads for detachably 70 connecting the same, a threaded bolt connected to said retaining ring and threadedly 75 engaging the threaded nut.

In testimony whereof, I affix my signature.

HAROLD A. McCLELLAN.
